CLAIM

The ornamental design for a switchplate for circuit breaker compartments.

DESCRIPTION

FIG. 1 is a front elevational view of a switchplate for circuit breaker compartments showing our new design; FIG. 2 is a side elevational view taken from the left of FIG. 1;

FIG. 3 is a rear elevational view thereof;

FIG. 4 is a side elevational view taken from the right of FIG. 1;

FIG. 5 is a front, top perspective view thereof;

FIG. 6 is a rear, top perspective view thereof;

FIG. 7 is a rear, bottom perspective view thereof.
